BAGGAGE CARRIER

Pasquale Rossi, New York, N. Y., assignor of one-half to Anastasio Petrocelli, Hoboken, N. J.

Application December 4, 1933, Serial No. 700,763

8 Claims. (Cl. 190—38)

This invention relates to new and useful improvements in a baggage carrier.

The invention has for an object the construction of a baggage carrier which simulates a grip in every respect, but which is provided with the addition of castors so that it may be pushed along upon the ground.

As a further object of this invention it is proposed to so mount the castors upon the baggage carrier that they may assume a position within the carrier, when they are not needed, and assume a position outside in position so that the baggage carrier may be pushed along the ground, thereon.

Still further the invention contemplates mounting the castors on a movable member adapted to assume a position in which the castors are disposed within the carrier and another position in which they are outside the carrier ready for use.

Still further it is contemplated to hingeably mount the member carrying the castors in a manner so that it may assume the two positions desired.

Furthermore as another object of this invention it is proposed to mount the member hingedly upon one side and arranged so that it may move from a position along one side of the baggage carrier to a position along one end.

Still further it is proposed as a modification to arrange the member pivotal upon one of its center lines so that it may pivot from a position in which the castors are disposed within the carrier to a position in which the castors are located outside.

Still further it is proposed to associate novel holding means with the member for holding the member in either of the positions desired.

As another object of this invention it is proposed to provide an arrangement whereby the castors may be raised and lowered to various degrees so as to adapt them to be replaced for the convenience of the user.

Still further an arrangement is proposed whereby the castors may assume various adjusted positions upon the member or be removed entirely.

Another one of the objects of this invention is the construction of a device as mentioned which is simple and durable and which may be manufactured and sold at a reasonable cost.

For further comprehension of the invention, and of the objects and advantages thereof, reference will be had to the following description and accompanying drawings, and to the append-

ed claims in which the various novel features of the invention are more particularly set forth.

In the accompanying drawings forming a material part of this disclosure:—

Fig. 1 is a perspective view of a baggage carrier constructed according to this invention. 5

Fig. 2 is a plan view of Fig. 1.

Fig. 3 is a fragmentary perspective view of the lower corner of the baggage carrier illustrated in Fig. 1 as seen as though looking in the direction 10 of the line 3—3 of Fig. 1.

Fig. 4 is a fragmentary vertical sectional view taken on the line 4—4 of Fig. 3.

Fig. 5 is an elevational view looking in the direction of the line 5—5 of Fig. 4. 15

Fig. 6 is an elevational view looking in the direction of the line 6—6 of Fig. 5.

Fig. 7 is a sectional view taken on the line 7—7 of Fig. 6.

Fig. 8 is a fragmentary sectional view of the 20 lower portion of the baggage carrier constructed according to a modification of this invention.

Fig. 9 is a fragmentary elevational view looking in the direction of the line 9—9 of Fig. 8.

Fig. 10 is a side elevational view of a baggage 25 carrier constructed according to a still further modified form.

Fig. 11 is an elevational view looking in the direction of the line 11—11 of Fig. 10.

Fig. 12 is a sectional view taken on the line 30 12—12 of Fig. 11.

Fig. 13 is a view similar to Fig. 11 but illustrating another modified form.

Fig. 14 is a sectional view taken on the line 35 14—14 of Fig. 13.

The baggage carrier according to this invention comprises a conventional baggage carrier 10 which is in the form of a receptacle having a hinged cover 11 and means for normally holding the cover closed. As illustrated straps 12 are provided for this purpose. The baggage carrier is provided with a handle 13 upon one side of it which may be conveniently carried as a conventional grip. At one end the baggage carrier is provided with a handle 14 which is hingedly mounted at one end 15 upon a bracket formed with a stop 16 so as to limit pivoting of the handle to a substantially vertical position as indicated by the dot and dash lines in Fig. 1. Several bolts 17 project from the end of the baggage carrier 40 and are engageable through openings in the end of the handle so as to provide for locking the handle in a fixed position. When the handle is locked as shown the baggage carrier may be conveniently gripped and lifted. When the handle 45 50 55

is pivoted to the dot and dash position it serves as a handle by which the baggage carrier may be conveniently pushed along the ground, upon castors, as hereinafter further described.

- 5 At the bottom end of the baggage carrier, a member 18 is movably mounted and arranged to assume one or another position hereinafter further described. Castors 19 are mounted upon the member 18 and are adapted in one position to 10 be disposed within the baggage carrier and in another position of the member to be located outside of the carrier. A means is provided for holding the member 18 in either of its positions. A partition 20 is formed within the baggage carrier and serves to provide a compartment into 15 which the castors 19 may normally be disposed when the member 18 is in a position in which the castors are disposed within the baggage carrier.
- 20 The member 18 is illustrated in Figs. 1, 3 and 4 and comprises a flat member engaging over an opening formed in the side of the baggage carrier so as to close the compartment formed by the partition 20. The member 18 is hingedly 25 mounted at one side upon the bottom corner of the baggage carrier and the hinge is arranged so that the member 18 may assume the position illustrated by the full lines in Fig. 4 or may be pivoted to a position flat against the bottom of 30 the baggage carrier as illustrated by the dot and dash lines in Fig. 4.

The means for holding the member 18 in one or the other of its positions, comprises a latch mounted upon the member 18 consisting of a 35 casing 22 from which a bolt 23 is resiliently projected. The spring 24 is mounted within the casing to extend the bolt. A transverse pin 25 is engaged through the bolt 23 and passes through elongated slots 26 formed in the casing 22 and 40 in the member 18 whereby the pin 25 may be moved from either side of the member 18 to retract the bolt. The bolt 23 when the member 18 is in its closed position, acts against the inner side of the material of the baggage carrier which 45 surrounds the opening in which the member 18 is located. When the member 18 is pivoted to its outside position then the bolt 23 engages within a keeper member 27 mounted upon the bottom of the baggage carrier. An opening 28 is also 50 formed in the bottom of the baggage carrier through which a portion of the pin 25 may extend so that the pin does not produce an obstruction which would restrain the member 18 from assuming its correct position.

55 The castors or wheels 19 are arranged upon a detachable standard so that its position as regards the member 18 may be varied. The standard which supports the castors 19 (or wheels) comprises a pair of closely spaced parallel plates 60 29 having their base ends 30 turned away from each other and attached upon the member 18. Another plate is bent upon itself so as to have opposed sides 31 and a bent center 32 connecting these sides. The sides 31 engage between the plates 29 and maintain their positions due to 65 bolts 33 which pass through the plates 29 and which are screwed tight. The bolts 33 pass through slots 34 formed in the plates 31 so that when the bolts 33 are loosened the plates 31 may 70 be moved relative to the plate 29 to adjust the distance of the castors from the member 18. A shaft 35 is engaged through the bend 32 and the castors or wheels 19 are mounted upon the shaft.

In Figs. 8 and 9 a modified form of the invention has been disclosed in which a member 18' is

illustrated for carrying the castors but arranged to pivot along the center line with the castors disposed inwards or outwards. More particularly a transverse pintle rod 36 passes through the center of the member 18' and has its ends engaged into the sides of the material surrounding the opening in which the member 18' is set. The member 18' in this form of the invention is set into an opening formed in the bottom end of the baggage carrier. The member 18' is adapted 10 to pivot so that either face is extended outwards. A means is provided for holding the member 18' in either of these positions and comprises a pair of latches mounted upon opposed edges but on the same side of the member 18' and adapted to 15 engage the material immediately surrounding the opening into which the member 18' is set.

Each of these catches are identical in construction to the construction described relative to the catch in Fig. 4. Similar parts of the 20 catches will be recognized by corresponding reference numerals. It should be noticed that the bolts 23 of the catches extend sufficiently so as to engage the edges of the material surrounding the opening in which the member 18' is set. 25 Each of the catches are provided with a transverse pin 25 which engages through the slots 26 so that the catches may be operated from either side of the member 18'. The dot and dash circle 37' in Fig. 8 illustrates the path of the member 30 18' as it is turned about its pintle rod 36. The castors or wheels 19 are mounted upon standards identical in construction to those described relative to Figs. 4-7 inclusive. This standard is mounted upon one side of the member 18' as 35 clearly illustrated in Fig. 8. In other respects this form of the invention is similar to the one previously described and other similar parts may be recognized by corresponding reference numerals.

In Figs. 10-12 inclusive another modified form of the invention has been disclosed in which the castors are mounted upon the removable piece. According to this form of the invention the baggage carrier is equipped with the member 18' 45 which is provided with a pintle rod 36 and which is mounted within the baggage carrier 10 as described relative to the construction illustrated in Figs. 8 and 9. Upon one side of the member 18' there is mounted a guide member 38 which is 50 equipped with closed flanges on the sides thereof producing a track in which a slide 39 may be moved. One end of the slide 40 of the slide 39 is bent at right angles to the slot and constitutes 55 a handle by which it may be conveniently gripped.

The other end of the slide is provided with a catch section 41 adapted to cooperate with another catch section 42 mounted upon the member 18'. These catch sections 41 and 42 are so constructed that they may be engaged with each other to hold the slide 39 in place or they may be disengaged so that the slide 39 may be moved longitudinally out from the guide 38. The standard which supports the castors or wheels 19 is mounted upon the slide 39. The details of the 60 standard and the castors are similar to those described relative to Figs. 4-7 inclusive, and similar parts may be recognized by corresponding reference numerals. Auxiliary single castors 19' are also secured to the slide 39 by standards 29' which form bends 32' in which shafts 35' are secured and the castors or wheels 19' are mounted upon this shaft. According to this form of the invention the slide 39 may be removed and the castors 65 completely removed if desired. This allows for a 70 75

replacing of another slide with different castors, perhaps of a different size, or arrangement to be substituted.

In Figs. 13 and 14 another modified form of the device has been illustrated in which the member 18' is provided with a casing 43 which is provided with end walls 44 and side walls 45. A screw 46 is rotatively mounted through the end walls 44 and has a projecting head 47 by which it may be readily turned. A follower 48 is threadedly engaged upon the screw 46 and is disposed between the side walls 45 so as to be prevented from rotating and limited to move longitudinally along within the casing 43 as the screw 46 is rotated. The standard which supports the castors or wheels 19 is mounted upon the follower 48. The details of the standard and the castors are similar to those illustrated relative to Figs. 5-7 inclusive and the various parts may be recognized by the corresponding reference numerals.

According to this form of the invention the location of the castors upon the member 18' should be varied by merely turning the screw 46 which causes the follower 48 to move and correspondingly carry the castors. With this arrangement it is possible to locate the castors 19 at different distances from the lowermost corner of the baggage carrier and from a fixed auxiliary wheel 19' which is secured to the end wall 44 and member 18'.

The operation of the device is as follows:—Normally the member should be located so that the castors are disposed within the baggage carrier. The baggage carrier may be used in conventional manner, that is for the storing of clothes or other articles. It may be carried about by the handles provided for it. The receptacle constituting the carrier may be opened or closed in any conventional fashion. In the event that the baggage carrier is loaded with heavy material, too heavy to allow complete carrying by the handles then the member which supports the castors should be detached so that the castors are disposed outside upon one end of the material. Then the baggage carrier may be rested upon the ground on these castors and pushed along similar to a hand truck. With this arrangement it is possible to carry a very heavy load for any desirable distance.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A baggage carrier, comprising a receptacle for baggage and having an opening in the side wall at one corner, a member movably mounted on one end thereof upon said corner forming a closure for said opening and adapted to assume a position flat against the end of the receptacle, castors mounted upon one side of said member, and means holding said member in a closed position with the castors disposed within the baggage carrier and in an open position with the castors extended below the end of the baggage carrier.

2. A baggage carrier, comprising a receptacle for baggage and having an opening in the side wall at one corner, a member movably mounted on one end thereof upon said corner forming a closure for said opening and adapted to assume a

position flat against the end of the receptacle, castors mounted upon one side of said member, and means holding said member in a closed position with the castors disposed within the baggage carrier and in an open position with the castors extended below the end of the baggage carrier, said castors being mounted upon a plate adjustably mounted on a standard mounted on said member whereby the relative distance of the castors from the member may be adjusted.

3. A baggage carrier, comprising a receptacle for baggage and having an opening in the side wall at one corner, a member movably mounted on one end thereof upon said corner forming a closure for said opening and adapted to assume a position flat against the end of the receptacle, castors mounted upon one side of said member, and means holding said member in a closed position with the castors disposed within the baggage carrier and in an open position with the castors extended below the end of the baggage carrier, comprising a catch mounted upon said member and engageable selectively with one of a pair of keepers located on the side and end of said receptacle to hold the member in one or the other positions.

4. A baggage carrier, comprising a receptacle for baggage, a member movably mounted on a pivot on one end of said receptacle, castors mounted upon one side of said member, and means holding said member in one position with the castors disposed through an opening and within the baggage carrier and in another position with the castors extended below the end of the baggage carrier, said member being pivotally mounted by said pivot upon one of its center lines and normally disposed within said opening formed in the bottom end of said baggage carrier and adjustable to either of said positions.

5. A baggage carrier, comprising a receptacle for baggage, a member movably mounted on a pivot on one end of said receptacle, castors mounted upon one side of said member, and means holding said member in one position with the castors disposed through an opening and within the baggage carrier and in another position with the castors extended below the end of the baggage carrier, said member being pivotally mounted by said pivot upon one of its center lines and normally disposed within said opening formed in the bottom end of said baggage carrier and adjustable to either of said positions, said castors being mounted upon a standard attached upon one side of said member.

6. A baggage carrier, comprising a receptacle for baggage, a member movably mounted on a pivot on one end of said receptacle, castors mounted upon one side of said member, and means holding said member in one position with the castors disposed through an opening and within the baggage carrier and in another position with the castors extended below the end of the baggage carrier, said member being pivotally mounted by said pivot upon one of its center lines and normally disposed within said opening formed in the bottom end of said baggage carrier and adjustable to either of said positions, said castors being mounted upon a standard attached upon a slide removable detachably mounted upon said member.

7. A baggage carrier, comprising a receptacle for baggage, a member movably mounted on a pivot on one end of said receptacle, castors mounted upon one side of said member, and means holding said member in one position with

the castors disposed through an opening and within the baggage carrier and in another position with the castors extended below the end of the baggage carrier, said member being pivotally mounted by said pivot upon one of its center lines and normally disposed within said opening formed in the bottom end of said baggage carrier and adjustable to either of said positions, said castors being mounted upon a standard attached upon a slide removable detachably mounted upon said member, said slide being mounted upon a guide member, and a catch upon said slide and member for detachably holding the slide in place.

8. A baggage carrier, comprising a receptacle for baggage, a member movably mounted on a pivot on one end of said receptacle, castors mounted upon one side of said member, and

means holding said member in one position with the castors disposed through an opening and within the baggage carrier and in another position with the castors extended below the end of the baggage carrier, said member being pivotally mounted by said pivot upon one of its center lines and normally disposed within said opening formed in the bottom end of said baggage carrier and adjustable to either of said positions, said casing member being attached upon said member and formed with opposed walls, a screw rotatively mounted through opposite walls of said walls, a follower threadedly engaged upon said screw and engaging against the other of said walls, and a standard mounted upon said follower and supporting said castors.

PASQUALE ROSSI.
